TREATMENT OF LIGHT PETROLEUM DISTILLATES

Arthur Lazar and Thomas F. McCormick, Associated, Calif., assignors, by mesne assignments, to Tide Water Associated Oil Company, San Francisco, Calif., a corporation of Delaware

No Drawing. Application January 24, 1936,
Serial No. 60,720

4 Claims. (Cl. 260—504)

This invention relates to an improved process of preparing sulphonc acids from petroleum.

Another object is to provide an improved process for isolating groups of aromatic hydrocarbons, or sulphonc acids derived therefrom.

Another object is to provide for the separation of a petroleum distillate so that substantially pure saturated hydrocarbons (paraffines and naphthenes) and pure aromatic hydrocarbons 10 can be recovered.

Further objects will become apparent as the invention becomes more fully disclosed herein-after.

Certain mineral oil distillates, such as those 15 produced from California crudes, contain appreciable quantities of non-hydrocarbon impurities. In refining such distillates, particularly those comprising the normal boiling point range of gasoline, petroleum spirits, and kerosene, it is 20 found that the presence of these non-hydrocarbons interferes to a certain extent with the usual treating methods applied on said distillates.

Chemically speaking these non-hydrocarbons 25 consist of organic acids, such as naphthenic acids, phenols, and the like, sulphur compounds of acidic nature like mercaptans and thio-phenols, other sulphur compounds, and nitrogen bases.

Inasmuch as organic acids and nitrogen bases 30 present in the distillates are attacked by sulphuric acid, these compounds should be removed before the distillates are treated with the concentration of sulphuric acid for the recovery of desired hydrocarbons herein set forth.

In addition it has often been found that distillates containing such impurities cause difficulties in subsequent processing. For example, if the distillates containing said non-hydrocarbons 35 are treated with liquid sulphur-dioxide or other solvents according to the well-known Edeleanu process, it has been found that salts of nitrogen bases and resinous deposits are formed in the 40 treating equipment. The salt crusts represent reaction products of sulphurous and sulphuric acid with nitrogen bases mixed with resinous 45 material, which has been formed by polymerization of the phenols. Such deposits often are quite troublesome and can be the cause of the emulsions in the SO_2 or other treating process, or, when accumulated in large quantities can interfere with heat transfer in the exchangers and 50 evaporators of the treating unit, or when accumulated in lines and pumps, can interfere with the throughput of the plant.

It is therefore an object of this invention to 55 submit mineral oil distillates composed of a plurality of fractions to a number of treating steps in the proper sequence and thereby to split the fractions up in such a manner that substantially 60 pure aromatic sulfonic acids are obtained which

heretofore could not be obtained from mineral oils in any appreciable quantity.

Broadly speaking, the invention involves the treatment of a petroleum distillate (cracked or uncracked) with specific reagents in such sequence of steps that such reagents, which cannot under usual conditions exercise their function of selectivity, are enabled to be applied with complete selectivity.

This will be better understood if, for instance, 10 the reactions of sulphuric acid with hydrocarbons is considered when a certain concentration of sulphuric acid is ineffective to dissolve, or react with, unsaturated and aromatic hydrocarbons while other concentrations may be used to effectively separate unsaturated and aromatic hydrocarbons from saturated hydrocarbons and from each other. In consequence, this selective action 15 of sulphuric acid and of solvents such as liquid sulphur dioxide, benzol-sulphur dioxide, phenol, furfural, nitrobenzene, dichlorethylether, a mixture of propane and cresylic acid, and like solvents, or a combination of any of these solvents with each other or with liquid SO_2 , for hydrocarbons and impurities in hydrocarbons, is so utilized herein that a refined petroleum distillate 20 of improved qualities is obtained while pure hydrocarbons of definite characteristics and pure by-products are made available for varied uses 25 in the arts.

Referring to the operation of the process, a 30 light raw distillate obtained from California crude petroleum, such as the gasoline, kerosene, or petroleum spirits fractions thereof is the original stock to be treated.

Such raw distillate may be, merely by way of 35 illustration and not of limitation, a selected cut from a crude oil within the boiling range of a specification gasoline desired as a final product, or of any desired cut within such boiling range suitable for treatment to provide a finished cut 40 available for blending to yield a specification gasoline.

If it be assumed that such raw distillate is from 45 a California crude oil, the same may contain fractions of the paraffine, naphthene, olefine, di-olefine, and aromatic hydrocarbons together with organic acids, nitrogenous bases, and various forms of sulphur compounds, and may have the following physical characteristics:

Grav. A. P. I.	50.7
I. B. P.	155
E. P.	470
Sulphur	per cent 0.12
Nitrogen	do 0.08
Aniline Pt	° F 127

As before stated, it must be understood that steps of the process are particularly applicable to any selected overhead distillate from petroleum

- which ranges in volatility from the light gasoline cuts right through the various boiling ranges of petroleum spirits, kerosene, gas oil, spindle oil, and spray oils down to heavy viscous lubricating oils and the treatment of a gasoline fraction is described as being illustrative of a fuller range of operations which will include the recovery of a very superior motor fuel as well as other included purified products.
- 10 The raw distillate, depending on its boiling range, is subjected to a series of steps for the removal of impurities and recovery of finished products.

Preferably the raw distillate is first treated 15 with a solution of alkali, such as caustic soda solution of a concentration of about from 15° Bé. to 30° Bé. which serves with proper agitation to combine with the organic acids in the distillate and to break up the combination between the 20 organic acids and nitrogen bases in the distillate while polymerizing certain unstable resinous compounds therein and the thus reacted caustic with absorbed material is removed from the distillate.

25 The distillate is then agitated with sufficient quantity of dilute sulphuric acid, which is of a concentration less than 90% acid and preferably of about 50% to 60% acid, which serves to react with nitrogenous bases in the distillate and the 30 spent acid is then withdrawn to leave the distillate free from organic acids and nitrogenous bases.

35 The spent acid may be separated by gravity settling or the settling can be accelerated by centrifugal action. Any of the well known methods can be used for removing the spent acid in order to prepare the distillates for solvent refining. In commercial operation certain stocks may require the neutralization of the last traces of sulphuric 40 acid with caustic soda or other alkalies before solvent refining.

45 The thus withdrawn caustic solution may be acidified with fresh acid which serves to throw the absorbed organic acids out of solution for recovery as such, while the spent dilute acid may be causticized with fresh caustic soda solution to throw out the nitrogenous bases for recovery as such.

50 It must be understood that while the above described removal of organic acids and nitrogenous bases is preferably done as the first step of the process so that the remaining steps of the process may be more clearly illustrated and facilitated, such removal is not essential as a first step but 55 may be performed as a later step as will be later more fully described.

55 The thus purified distillate is then subjected to treatment with a solvent such as liquid sulphur dioxide, or any of the other described and well known selective solvents, in a well known manner to separate the distillate into two portions or layers.

60 The upper layer is known as the raffinate composed of the paraffine and naphthene series of hydrocarbons and the lower layer (termed the extract) consists mainly of the olefine, diolefine, and aromatic series of hydrocarbons together with a certain percentage of saturated hydrocarbons 65 of the paraffine and naphthene series and certain sulphur compounds.

65 Depending on required uses, the extract after removal of SO₂ therefrom may either be used as is or first subjected to treatments in certain steps 70 to derive certain products or to leave a fraction

75 of high anti-knock value to be added to said raffinate.

The extract of gasoline boiling range is first treated with sulphuric acid of a concentration from 90% H₂SO₄ up to a fuming acid containing 5 20% SO₃, depending on the action desired on the extract, and all treatments of the distillate or extract with the reagents described and used herein are preferably conducted for the fullest contact efficiency as for example in accordance 10 with the method disclosed in a co-pending application of Edwards and Stark, Serial No. 532,000, filed April 22, 1931, issued as U. S. Letters Patent 2,052,852, September 1, 1936, the range of temperatures used therewith being regulated from 15 below 0° F. up as high as 80° F., depending on the solvent or sulphonating effect required from the sulphuric acid.

If organic acids and nitrogenous bases have 20 already been removed from the extract of definite boiling range, the extract will be contacted with sulphuric acid of 90% concentration, or greater, in such quantity and at such temperature as to leave an extract composed mainly of hydrocarbons of a cyclic structure, such as aromatics 25 and hydroaromatics.

In addition to the many functions already described the practically complete removal of active sulphur compounds is desired during the acid treatment of sulphur dioxide or other solvent 30 refined extracts. This is accomplished by the use of relatively low sulphuric acid rates normally below ten (10) pounds per barrel and not over 30 pounds per barrel on extracts of high sulphur content. Solvents manufactured in this manner 35 have excellent stability and are particularly adapted for use by the paint, varnish, and lacquer industry where stability against light and weathering is of primary importance and there is no tendency for corrosion due to the elimination of active sulphur compounds.

In order to obtain other products, if it is not desired to use the treated extract as above set forth, or as raw material for solvents, the whole, or part, of the extract may be further treated 45 with up to 100% or more of its volume with concentrated sulphuric acid (varying from 90% acid up to 20% fuming acid) under such conditions of temperature that all the aromatics in the extract are sulphonated and the remainder of the 50 extract will consist of more saturated hydrocarbons (mainly naphthenes and hydroaromatics) which, when neutralized, are especially valuable as special petroleum spirits, thinners, Stoddard solvent, or similar solvents in which extremely 55 low sulphur content, or complete freedom from both active and less active sulphur compounds is required.

If the extract has been treated in the first place with but a small amount of concentrated 60 sulphuric acid, for the production of solvents or motor fuel not more than about 10 pounds of acid to the barrel, merely for partial sulphur reduction, the acid sludge therefrom may be discarded, but if it has been treated with acid up 65 to as high as 30 pounds of acid per barrel of extract for further sulphur reduction, the acid sludge may contain a similar concentration of sulphonate acids as is contained in the acid sludge resulting from treatment of the extract with 70 100% of its volume of concentrated sulphuric acid, and the succeeding steps are applicable thereto.

75 Depending on the sulphur content of the extract the sulphuric acid treatment may be car-

ried out in one or more steps but preferably in at least two stages for the subsequent recovery of sulphonic acids, naphthenes, and pure aromatics. The initial purification with strong acid is particularly necessary if the sulphur content of the extract is high, and may require up to 30 pounds of sulphuric acid per barrel for desulphurization purposes. The degree of sulphuric acid treatment in one or more stages will depend on the sulphur content of the extract and quality and purification of solvents, motor fuel, sulphonic acids, saturated oils, and other by-products desired. In the acid treatment with two or more stages the initial treatment removes the more easily attacked substances such as non-hydrocarbons, di-olefines, etc. and the subsequent treatments will start to actively sulphonate aromatics.

The acid sludges from the later treats may be contaminated with a small quantity of non-hydrocarbons and sulphonic acid recovery is somewhat more difficult than when these non-hydrocarbons are completely eliminated and only the acid sludges from the concentrated heavy acid treatment of up to 100% by volume or more of sulphuric acid is used.

To definitely illustrate, we can treat a high sulphur extract with 30 pounds per barrel of strong acid in six treats of five pounds per barrel each. The first one or two treats will yield sludges contaminated with the reaction products of non-hydrocarbons which may be discarded in order to avoid contamination of sludges later derived. The remaining treats yield sludges containing substantial quantities of sulphonic acids as the sulphuric acid treatment starts to attack the aromatic hydrocarbons to an appreciable extent. These sludges may be a suitable source of slightly contaminated sulphonic acids although more purified by-products are obtained particularly pure sulphonic acids from acid sludges formed in later treatment.

With acid sludges containing relatively high percentages of sulphonic acids, as described, novel steps are next used on said sludges for the recovery of sulphonic acids and pure aromatics, and such steps are applicable to any acid sludges containing sulphonated compounds whether derived from the before described treatment or derived from any other sulphuric acid treatment of other hydrocarbons and shows great improvement over the usual and conventional methods of treating acid sludges.

In the usual method, the acid sludge consisting of sulphonic acids and sulphuric acid is neutralized with calcium hydroxide which converts all the acids present into calcium salts, such as calcium sulphate and calcium sulphonates, which mixture is washed with water to leach out the water soluble sulphonates and leaves the water insoluble calcium sulphate, and the sulphonates are then concentrated. This procedure is very tedious and costly as the sulphuric acid is converted into calcium sulphate, a product of low value. The neutralization costs are greater and the sulphuric acid cannot be recovered for future use. The calcium sulphates must also be acidified to obtain free sulphonic acids.

On the other hand, the acid sludges derived from the above described treatments may be mixed with a volume of water amounting to about one-third ($\frac{1}{3}$) of the sulphuric acid used on the extract which, after agitation and settling, provides two layers of liquids due to the salting out effect of the free mineral acid on the free sulphonic acids. As a result, the mineral acid con-

tent of the upper layer is greatly reduced and the lower layer retains a minimum of organic compounds.

In consequence the upper layer consists mainly of sulphonic acids and the lower layer consists mainly of sulphuric acid of a relatively low degree of concentration.

The lower layer may then be drawn off and distilled under such conditions of temperature and pressure that any traces of sulphonic acids contained therein will be split by heat to free the aromatic hydrocarbons which can be carried off as an overhead vapor and condensed to yield pure aromatics. The liquid remaining in the still consists of dilute sulphuric acid which may be concentrated and recovered in any well known manner for use and is especially adapted for such recovery because of its purity and freedom from nitrogen bases earlier removed from the distillate.

While small amounts of aromatics may be further recovered from the dilute sulphuric acid during concentration, the sulphur compounds and other impurities contained in the acid sludge are apparently destroyed during distillation and concentration because the aromatics recovered during these steps are free of such impurities.

The upper sulphonic layer can be isolated for further purification, or treated by a hydrolizing steam distillation to drive off the aromatics as overhead which are condensed and may be mixed with the aromatics derived from the lower layer while the remainder of the upper layer consists of dilute sulphuric acid which can be concentrated for use as described for the remainder of the lower layer.

In the event that the upper, or sulphonic, layer is permitted to stand for some time without distillation, it has been noted that there is a tendency for the formation of crystals of pseudocumene sulphonic acid and such crystals may be readily separated from said sulphonic layer by a centrifuge prior to subjecting the remainder of the sulphonic layer to the hydrolizing steam distillation before described.

The aromatic hydrocarbons thus derived by the aforesaid treatments of the upper and lower layers are exceptionally pure and require only the usual neutralizing and washing treatments prior to use and such purity is due to the prior treatment of the distillate for the removal of organic acids which otherwise would contaminate the sulphonic layer and cause secondary reactions. It may readily be perceived, for instance, that if phenols were not thus removed they would be sulphonated along with the aromatics and then later reappear as contaminating substances in the resultant products.

At the same time it must be noted that while the described removal of organic acids and nitrogenous bases in the original raw distillate is preferably accomplished as an initial step of the process, such removal may be effected at any time prior to, or as far as the nitrogen bases are concerned, during the initial step of subsequent treatment with strong sulphuric acid.

The SO₂ extract may therefore be treated with caustic solution for the removal of organic acids at any time prior to treatment with concentrated sulphuric acid.

Likewise if the SO₂ extract is first treated with caustic soda solution and then treated with concentrated sulphuric acid in relatively small volume, as described, so as only to effect sulphur removal with low sulphonation of aromatics, the extract will then be free of nitrogenous bases be-

cause they will be removed by the concentrated acid and also be free of organic acids and thus will be in a condition suitable for use, or for sulphonation to yield pure aromatics.

It is apparent that by suitable variations of the treatments with concentrated sulphuric acid with regard to time of contact, temperature of contact, method of contact, quantity of acid, concentration of acid, the extract can be modified to yield products suitable for the uses enumerated and that such products may yield various types of aromatics.

For instance, if the extract is treated with acid in a plurality of steps including a first step with a small quantity of acid, the aromatics most readily attacked by acid can be extracted first and successive variations of treatment can be used to provide pure aromatics of desired characteristics. Such treatments by selective reactivity of sulphuric acid accomplishes partial separation without distillation.

Modifications and alternations of treatment of the raw distillate are provided in addition to those stated.

For instance, while the treatment of a raw gasoline distillate has been described to yield a finished motor fuel of high anti-knock value, if the raw distillate initially is of gasoline boiling range, or of any other overlapping boiling range, the SO_2 or other extract derived therefrom may be distilled to yield a light fraction within the gasoline boiling range and bottoms heavier than such range. Such bottoms can then be recovered as a dark liquid of high fluidity and penetrating power suitable for use for the destruction of plant life, or a so-called weed killer, as a fuel for certain types of Diesel engines, a cutback oil or solvent for asphalt, pitch, coke, heavy residua, or due to its penetrating power and wetting ability, as a flotation oil.

The light fraction may then be treated according to the described steps for the same uses as described.

It is thus clear by the steps enumerated that the treatment of a raw distillate may be so conducted that not only is the distillate recovered in a pure state, but that every step assures the recovery of products of value which heretofore in most cases have been useful in only a minor degree.

It is understood that in referring to the boiling or distillation range of any particular distillate that the limits of such distillation range are those included in the every day, or commercial sense, such for instance as are found in the U. S. Government or A. P. I. specifications.

It will be noted that, while certain of the described steps have been shown as batch operations for the sake of simplicity, many of the same may be carried on in well known continuous operations and therefore such descriptive operations impose no limitations beyond the scope of the appended claims.

Although the above inventions have been directed towards the processing of distillates and the recovery of valuable by-products therefrom, it should be understood that we also include the refinement of those light and heavy crudes containing substantial quantities of non-hydrocarbons heretofore defined. Certain California crudes such as those originating from the Ventura, Southern California, Kettleman Hills and Belridge fields contain appreciable quantities of non-hydrocarbons and/or unsaturated and aromatic hydrocarbons which are desirable sources

of by-products. Depending on the nature of the crude and the particular by-product recovery desired distillation may be first used to greater advantage in the later stages of processing and this mode of operation is also claimed, utilizing the inventions fully described for the preferred treatment of light distillates.

This application is a continuation in part of our co-pending application Serial No. 521,626, filed March 11, 1931.

We claim:

1. A process of treating oils which comprises: treating a petroleum oil containing aromatic hydrocarbons with separate dosages of an aqueous alkaline solution to remove organic acidic compounds and of sulfuric acid having a concentration less than 90% H_2SO_4 to remove nitrogenous bases, extracting the thus purified oil with a selective solvent whereby an extract rich in aromatic hydrocarbons is obtained, sulfonating said extract with sulfuric acid of a concentration greater than 90% H_2SO_4 , and recovering the sulfonated products.

2. A process of treating oils which comprises: treating a petroleum oil containing aromatic and unsaturated hydrocarbons with separate dosages of an aqueous alkaline solution to remove organic acidic compounds and of sulfuric acid having a concentration less than 90% H_2SO_4 to remove nitrogenous bases, extracting the thus purified oil with a selective solvent whereby an extract containing aromatic and unsaturated hydrocarbons is obtained, treating said extract with sulfuric acid of a concentration greater than 90% H_2SO_4 first at a rate of less than 30 pounds of acid per barrel of oil to remove said unsaturated hydrocarbons then at a rate up to 100% acid by volume to sulfonate said aromatic hydrocarbons, and recovering the sulfonated aromatic hydrocarbons.

3. A process of treating oils which comprises: treating a petroleum oil containing aromatic hydrocarbons with 15° to 30° Bé. caustic soda solution, removing the spent caustic solution, contacting the treated oil with sulfuric acid of a concentration of 50% to 60% H_2SO_4 , removing the acid solution, extracting the contacted oil with a selective solvent whereby an extract rich in aromatic hydrocarbons is obtained, sulfonating said extract with sulfuric acid of a concentration greater than 90% H_2SO_4 , and recovering the sulfonated products.

4. A process of treating oils which comprises: treating a petroleum oil containing aromatic and unsaturated hydrocarbons with 15° to 30° Bé. caustic soda solution, removing the spent caustic solution, contacting the treated oil with sulfuric acid of a concentration of 50% to 60% H_2SO_4 , removing the acid solution, extracting the contacted oil with a selective solvent whereby an extract containing aromatic and unsaturated hydrocarbons is obtained, treating said extract with sulfuric acid of a concentration greater than 90% H_2SO_4 at a rate of less than 30 pounds of acid per barrel of oil sufficient to sulphonate the unsaturated hydrocarbons without substantial sulphonation of the aromatic hydrocarbons, removing the spent acid, treating the thus purified oil with sulfuric acid of a concentration greater than 90% H_2SO_4 at a rate up to 100% by volume to sulfonate said aromatic hydrocarbons, and recovering the sulfonated aromatic hydrocarbons.

ARTHUR LAZAR.

THOMAS F. McCORMICK. 75
